(57) **CLAIM**

The ornamental design for a battery charger for earphones, as shown and described.

DESCRIPTION

FIG. 1 is a front, right side perspective view of a battery charger for earphones;

FIG. 2 is a rear, left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is an enlarged cross-sectional view of the battery charger for earphones taken in the direction of line 8-8 of FIG. 3;

FIG. 9 is an enlarged cross-sectional view of the battery charger for earphones taken in the direction of line 9-9 of FIG. 7;

FIG. 10 is a front, right side perspective view of the battery charger for earphones showing an open lid state;

FIG. 11 is a rear, left side perspective view thereof;

FIG. 12 is a front elevational view thereof;

FIG. 13 is a rear elevational view thereof;

FIG. 14 is a top plan view thereof;

FIG. 15 is a bottom plan view thereof;

FIG. 16 is a right side elevational view thereof;

FIG. 17 is a cross-sectional view of the battery charger for earphones taken in the direction of line 17-17 of FIG. 12;

FIG. 18 is an enlarged cross-sectional view of the battery charger for earphones taken in the direction of line 18-18 of FIG. 16; and,

FIG. 19 is a reference perspective view of the battery charger for earphones, showing an open lid state in a condition of use.

(Continued)

The dashed broken lines in the drawings depict portions of the battery charger for earphones that form no part of the claimed design. The dot-dot-dashed broken lines showing earphones in FIG. 19 depict environment and forms no part of the claimed design.
